Fig. 5

FIG. 1 is a side elevational view of a portable lubrication unit embodying my new design.

FIG. 2 is a side elevational view thereof.

FIG. 3 is a rear elevational view thereof.

FIG. 4 is a front elevational view thereof.

FIG. 5 is a top plan view thereof.

The double hose element and the outlet cord shown in FIGS. 1 and 2 are shown broken away to indicate indeterminate length. Said elements have been omitted from FIGS. 3, 4 and 5 for convenience of illustration.

I claim:

The ornamental design for a portable lubrication unit, substantially as shown and described.
